US00D688131S

(12) **United States Design Patent**
Crawford et al.

(10) **Patent No.:** **US D688,131 S**
(45) **Date of Patent:** **** Aug. 20, 2013**

(54) **CONTAINER**

(75) Inventors: **John C. Crawford**, Mahopac, NY (US);
Christopher Hart, Chicago, IL (US);
Stacy Castro, Chicago, IL (US)

(73) Assignee: **Colgate-Palmolive Company**, New York, NY (US)

(**) Term: **14 Years**

(21) Appl. No.: **29/424,010**

(22) Filed: **Jun. 7, 2012**

(51) **LOC (9) CL.** **09-01**

(52) **U.S. CL.**
USPC **D9/529**; D9/565; D9/573; D9/575;
D9/449

(58) **Field of Classification Search**

USPC D9/516, 529-530, 537-546, 549-550,
D9/552, 554, 556, 563, 565, 567, 569, 574-575,
D9/682-694, 435, 446-447, 449; 215/379,
215/381-384; 220/669, 675

See application file for complete search history.

(74) Attorney, Agent, or Firm — Judy W. Chung

(57) **CLAIM**

The ornamental design for a container, as shown and described.

DESCRIPTION

FIG. 1 is a top, front, left side perspective view of a container according to a first embodiment of the new design;
FIG. 2 is a front elevational view thereof;
FIG. 3 is a rear elevational view thereof;
FIG. 4 is a left side elevational view thereof;
FIG. 5 is a right side elevational view thereof; and,
FIG. 6 is a top plan view thereof.

1 Claim, 4 Drawing Sheets
